CLAIM

The ornamental design for an undercarriage track shoe for
mobile earthmoving machine, as shown and described.

DESCRIPTION

FIG. 1 is a perspective view of an undercarriage track shoe
for mobile earthmoving machine showing our new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
Grayscale shading illustrates contour.

The dot-dash broken lines illustrate unclaimed boundaries
and form no part of the claimed design. The faded portions
outside the dot-dash broken lines form no part of the claimed
design.
